UNITED STATES PATENT OFFICE.

ANTON N. HORNUNG, OF LOS ANGELES, CALIFORNIA.

HOLDER AND CLOSURE FOR OPEN-MOUTH CONTAINERS.

Application filed September 9, 1926. Serial No. 184,384.

It is customary to pack lard in containers having an open mouth at one end which is normally closed by a removable lid. Such containers are usually tin cans or wooden buckets, and each contains a considerable quantity of lard so that it is heavy to lift and such containers are usually stood on their bottoms and normally closed with a tight closing lid that is somewhat difficult to remove from the mouth of the container and while it is desirable that the container be kept tightly closed, the difficulty of removing and replacing the lid or other closure when it is tightly closed, tempts the dealer to leave the lid partly open, thus giving access to dust and to insects that may find their way under the lid into the container. Lard is a semi-solid at ordinary temperatures and the containers are filled with the lard while it is hot and in a liquid state and the lard is allowed to cool and is then semi-solid and free from likelihood of running out when the open mouth container is tilted or up-ended, and an object of the invention is to hold the containers in such a position, and at such a height as will enable the tradesman to dispense it with the greatest ease and facility.

An object of this invention is to make provision whereby the opening of the container may be accomplished by a quick movement of one hand and the closing of the container may be effected by a similar movement of the hand in an opposite direction; and I have provided means whereby the lid of the container will be normally held in closed position by gravity and also by a spring latch and yet be in a position where it can be easily and quickly opened without the exercise of great force, or any manipulation of the latch.

In the invention, I have provided a support with a seat adapted to hold an open mouth container aslant, and provide a lid adapted to temporarily close the mouth of the container and provided with rearwardly extending means hingedly connected to the support and arranged at such an angle to the seat that when the lid and the support member fixed thereto are lowered by gravity, to mouth-closing position, the lid will stand aslant and fit tightly onto the open mouth; and when the lid is moved upward from the open mouth; it will swing backward out of the way; and in effecting this I have arranged the pivotal axes of the hinges in a line extending across, rearwardly of and above the level of the upper edge of the container so

that when the lid is raised from the slanting mouth to its highest position it will be rearwardly aslant, thus carrying the front edge of the lid well up out of the way of the attendant who is thus given freedom to dig the semi-solid lard out of the container with his paddle or spoon; and I have also provided a special construction of the lid supporting means carried by the container support and have provided a support having a hinged joint with a projecting ridge or tooth across one joint face and a complementary notch in the opposing joint face to receive said tooth; and I yieldingly hold the faces toward each other by resilient means that will be compressed when one face is turned relative to the other to cause the tooth to rise out of the notch and I have provided one of said faces with two notches at angles to each other to receive the tooth; one of said notches and the tooth being adapted to forcibly hold the lid in closed position, and the other notch and the tooth to less forcibly hold the lid in its raised position.

It is understood that the invention may be applied to other uses without departing from the principle of the invention.

Another object is to make provision of container holding means adapted to hold the containers in a convenient position to which and from which they may be conveniently moved.

This invention further provides a stand having jointed lid supporting means and lids supported thereby for readily closing and opening the mouth or open end of each container.

An object is to make safe and convenient provision for supporting the container closure, and for allowing it to be moved onto and from the open end of the container, and to cause the closure to remain firmly and securely in the open and closed positions respectively when placed there by the dealer.

Cheapness of construction and ease of installation and use are other objects and advantages of the invention.

Other objects, advantages and features of invention may appear from the accompanying drawings, the subjoined detailed description and the appended claims.

The accompanying drawings illustrate the invention.

Figure 1 is a front elevation of a stand having three seats and arranged to accommodate three large containers, one of such containers is shown seated and closed; another is shown

seated and open, and the third seat is shown with the lid therefor raised to admit a container into its seat which is shown vacant.

Fig. 2 is a fragmental view from above showing one rack fastened to a wall, a container in such rack and closed by a lid.

Fig. 3 is a view from the right end of Fig. 1, as the device would appear when all the containers are closed; broken lines indicate an open position of one of the lids.

Fig. 4 is a vertical section on line X*, Fig. 1.

Fig. 5 is a detail of the supporting arms at one edge of the lid which is omitted from the view; the lower arm is shown attached to a support, a fragment of which is shown.

Fig. 6 is a plan of the stand shown in Fig. 1 with lard containers in all the racks and each closed by its lid.

Fig. 7 is an enlarged fragmental detail more fully illustrating the lid and its supporting means.

Fig. 8 is a fragmental view looking from the right in Fig. 7, omitting the lid and showing the lid carrying arms in container closing position.

Fig. 9 is a fragmental view of one of the lid supports with parts in position for holding the lid open.

Fig. 10 is a view of the latching faces of the lid supporting joint, detached from each other.

The stand may have any suitable supports as the brackets provided with arms 1, top 2 and flat back 3 by which the bracket may be secured to an upright support as the wall 3'.

In the drawing, there is shown a rack frame formed of a front rail 4, a back rail 5, and cross pieces 6, 7, 8, 9 mounted on the brackets 1 and spaced apart and provided in the spaces 40 with seats to accommodate open mouthed containers 10, each seat being formed of a front rail 4 provided with an upwardly open concave notch 11 to accommodate the upper portion of the container; and the back rail 5 that is mounted on blocks 5' and is set rearwardly aslant, as clearly shown in Fig. 4 to form a stop and a support for the bottom of the container when the container is put into position to be supported by the seat.

The front slanting face of the rear rail 5 is spaced rearwardly from the front rail 4 to allow the center of gravity of the container to fall to the rear of the front rail when the lower side of the container is in the notch and the bottom of the container is against the rear rail.

12 is a back piece fixed to the rear ends of the cross pieces 6, 7, 8, 9, and the same is arranged to hold said cross pieces rigidly in position.

Between two adjacent cross pieces as between 6 and 7, and 7 and 8, and between 8 and 9 is arranged a pair of jointed lid supports, each support comprising a lower arm 35 rigidly fixed to the inner side of the cross

piece to which it belongs, and an upper arm 14 connected to the lower arm by a latching joint 15 and fixed to a lid 16; so that each lid 16 is supported by an individual pair of jointed supports. The arms 13 and 14 have an inward inclination and are measurably resilient and the space between the upper ends 17' of any pair of arms is normally somewhat greater than the diameter of the lid 16 so that when the parts are in position as indicated in Figs. 1 and 6, with the upper ends of the jointed support of any pair fixed to the opposite edges of the lid the lower ends of the upper arms 14 are normally held inwardly and the upper ends of the lower arms 13 are compressed or sprung inward therebetween.

The upper ends of arms 13 and the lower ends of arms 14 are provided with complementary friction, or latching, plates 17 and 18 and the adjacent faces of said plates are notched together, there being for this purpose grooves 19 and 20 in one of said plates and a tooth 21 on the other of said plates; and in the assembly of parts, the friction plates are placed together with the grooved face of one toward the toothed face of the other.

The grooved face is provided with a deep groove 19 and with a shallow groove 20, in angular relation to each other so that in one position of the toothed face 18 the tooth 21 will enter the deep groove 19 and in another position the tooth 21 will enter the shallow groove 20.

22 is a bolt having a head 23 on one end, and extending through a washer 24 and a helical spring 25 and through the friction joint, which is retained by the head of the bolt so that the joint is resiliently held by the pressure of the spring 25 to prevent upward movement of arms 14 and the lid from closed position without the application of some force in excess of that necessary to overcome gravity.

The grooves or notches 19 and 20 and the tooth 21 are angularly arranged relative to each other and to their respective arms 13 so that when the lid is down against the end of the container, as shown in solid lines in Fig. 3, the tooth 21 will be in the deep groove 19; and when the lid is up in the position shown in dotted lines in Fig. 3 the tooth 21 is in the shallower groove 20, and in order to move the lid from the closed to the open position, it is necessary to overcome the weight of the lid and its upper arms 14, and the pressure of the spring and the resistance of the tooth 21 in the deep notch 19.

The shallower notch 20 is preferably at right angles to the deep notch.

The lower arm 13 is provided with a crotch or angle foot 26 which is fixed to the cross piece 6 by screws 27.

The arms of the jointed support may be of

cast metal having the required resiliency to allow the arms to separate at the joint as the tooth climbs out of its notch when the lid is raised, and to allow the latching faces of the 5 arms to come together when the tooth enters the notch 19. The spring 25 makes such action certain.

The operation is simple, it only being necessary for the operator to apply one hand to 10 the lid and raise the lid to the open position shown in solid lines at the left and middle of Fig. 1, and in dotted lines in Fig. 3, and the tooth then enters the upright notch 20 and holds the lid in open position until it is 15 again adjusted by hand of the attendant to the closed position where it is held tightly by the resilience of the spring 25 and the pressure of tooth 21 in the deep groove.

I claim:—

20 1. A container lid, arms fixed to and projecting from said lid, and provided with hinge members having grooves in angular relation to each other; fixed supports hav-

ing teeth adapted to engage in said grooves respectively, there being deep grooves to receive the teeth when the lid is in one position and shallow grooves to receive the teeth when the lid is in another position. 25

2. A stand comprising a frame having seats to hold aslant open mouth containers; said frame comprising front and back rails and end and intermediate cross pieces; blocks on the cross pieces and rearwardly aslant container bottom supporting rails; the front rails having notches to receive the containers between the cross pieces; lids for the mouths of said containers; arms fixed to the lids and provided with hinge members; standards on the cross pieces; and hinge members on the standards pivoted to the hinge members on 40 said arms. 35

In testimony whereof, I have hereunto set my hand at Los Angeles, California, this 31st day of August, 1926.

ANTON N. HORNUNG.
